UNITED STATES PATENT OFFICE.

ALMA MEYER CAHN, OF STOCKTON, CALIFORNIA.

CHILD'S GARMENT.

Application filed October 14, 1921. Serial No. 507,742.

To all whom it may concern:

Be it known that I, ALMA M. CAHN, a citizen of the United States, residing at Stockton, county of San Joaquin, State of California, have invented certain new and useful Improvements in Children's Garments; and I do declare the following to be a full, clear, and exact description of the same, reference being had to the accompanying drawings, and to the characters of reference marked thereon, which form a part of this application.

This invention relates to improvements in outer clothing for infants and young children, the principal object being to provide a one-piece garment which may be easily put on, and will then completely cover the body and underwear of the child, and which may be opened up in such a manner, and without removal of the garment, as will enable the wearer, if a child of comprehensive age, to readily attend to its natural needs, and if worn by an infant unable to take care of itself, the design of the garment enables the nurse or parent to readily administer to the needs of the child and make any necessary changes in the way of under clothing, without removing the garment from the child.

I have also provided a garment having the above stated points of advantage, which may easily be made suitable for either a boy or a girl who have passed the age of helpless infancy.

The garment has been stated as being particularly an outer garment, but by making sundry minor alterations, such as will be obvious to a person skilled in the art, and by adopting of course a different quality of goods, it may serve equally well as an article of underwear, and as such will form a "union" suit such as is frequently worn by both children and adults.

A further object of the invention is to produce a simple and inexpensive garment and yet one which will be exceedingly effective for the purposes which it is designed.

These objects I accomplish by means of such structure and relative arrangement of parts as will fully appear by a perusal of the following specification and claims.

In the drawings similar characters of reference indicate corresponding parts in the several views:

Fig. 1 is a front view of the garment, as it would appear when being worn.

Fig. 2 is a similar view, showing the various fastenings undone and the front flap lowered.

Fig. 3 is a rear view of a modified form 60 of garment having a back flap.

Referring now more particularly to the characters of reference on the drawings, the numeral 1 denotes the body of the garment, provided at its upper end with a neck-orifice 2 and with sleeves 3 of any suitable length.

The back of the garment, of the type shown in Figs. 1 and 2, is solid, while the front, otherwise symmetrical in size and 70 shape with the back piece, is cut out as at 4 for a considerable portion of its area, the upper edge of this cut away portion extending preferably nearly across the entire front of the garment, as shown, while the sides 75 converge toward the lower end of the garment and terminate thereat.

The lower end of said cut away portion is of such a width in proportion to the total width of the garment at that point 80 that ample room is left for the fabric of the garment to encircle the legs of the wearer beyond the edges of the cut away portion.

The front of these leg encircling portions 85 are practically in the form of flaps 5, each having a fastening 6 such as is commonly used on frocks and the like at its lower inner edge which engages a corresponding or co-operating fastening 7 on the back piece 90 of the garment goods in symmetrical alinement therewith.

The front of the garment from the upper edge of the cut away portion 4 to the neck orifice 2 is slit vertically as at 8, one edge 95 overlapping the other somewhat, and co-operating fastenings 9 being provided to hold them together.

Shaped to cover the open portion 4 and overlapping the edges thereof is a flap 10, 100 which is permanently fastened to the body of the garment at the lower end thereof by a seam 11, but detachably secured to the goods around the remaining sides of the opening 4 by any suitably spaced number 105 of fastening members 12 of ordinary character.

The seam 11, instead of being in a straight line, is intentionally curved upwardly from the ends toward the center, as shown, so 110 that the goods between the legs of the wearer will naturally tend to fold together or gather

in the proper manner both as regards comfort and appearance.

The above described style of garment as will be evident is admirably suited to be worn by infants, since in order that the nurse or parent may attend to the needs of the child it is only necessary to lay him down, undo the flap 10 and draw it down, at the same time undoing the leg-enclosure fastenings 6, the flap portions 5 being then folded over to the sides. Thus the body and legs of the infant are freely exposed, without the necessity of removing the garment as a whole or undoing the front and upper fastenings 9 in such cases. At the same time, these upper fastenings may be released at any time without the necessity of opening the flap 10 all the way.

It will also be seen that it will be very easy to place the garment on an infant, since the sleeves are the only parts which form permanent enclosures and the garment may therefore be put on like a coat, and the goods then wrapped and fastened about the legs 25 and up the front.

This style of the garment is also particularly adapted for little boys' use, beyond the infant age.

For little girls of similar age however, an additional and openable back flap 13 is provided at the back of the garment as shown in Fig. 3, which flap is preferably symmetrical to and the same size as the front flap 10.

The garment is intended in all cases to have a free or loose fit, the sleeves to be short, and the lower end to terminate slightly above the knees of the wearer.

From the foregoing description, it will be readily seen that I have produced such a garment as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention, what I claim as new and useful and desire to secure by Letters Patent is:

1. A child's garment comprising a body, a portion thereof from above to the lower 55 end of the garment being cut away to form an opening intermediate the side edges of

the garment, flaps formed at the sides of said opening and serving as leg coverings with the back of the body portion and detachably fastened at their lower corners to the main body adjacent the central portion of the latter, and a flap covering the intermediate opening and detachably secured to the body goods thereabout.

2. A child's garment comprising a front and back body member having a neck orifice and sleeve members at the upper end, a portion of the front of the garment being cut away from a point below the neck orifice to the bottom of the garment to form an opening whereby the front of the garment for the vertical extent of the opening and to the sides thereof forms a pair of flaps to serve as leg enclosures with the back of the body, fastening means on the lower corners of said flaps, co-operating fastening means at the lower edge and near the central portion of the back of the body, and a flap covering said opening and detachably fastened to the first named flaps independent of the fastening means thereof with the body.

3. A child's garment comprising a front and back body member having a neck orifice and sleeve members at the upper end, a portion of the front of the garment being cut away from a point below the neck orifice to the bottom of the garment to form an opening whereby the front of the garment for the vertical extent of the opening and to the sides thereof forms a pair of flaps to serve as leg enclosures, detachably fastening means between the lower corners of said flaps and the back portion of the body near the center thereof, the front of the body being cut from the upper end of the opening to the neck orifice, detachably fastening means for holding the cut edges together, and a flap covering said opening and detachably fastened over the edges thereof.

4. A child's garment comprising a body portion provided with neck and sleeve orifices, the front of the body being cut from top to bottom and the lower portion of said cut being formed as an opening, flaps at the sides of the opening adapted to be placed about the legs of the wearer, detachable fastening means between the lower edges of the flaps and the main body portion, and a detachably secured flap covering said opening.

In testimony whereof I affix my signature.

ALMA MEYER CAHN.
